UNITED STATES PATENT OFFICE.

WILLIAM F. KIESEL, JR., OF ALTOONA, PENNSYLVANIA.

RAILWAY-CAR.

1,267,421.

Specification of Letters Patent. Patented May 28, 1918.

Application filed February 18, 1914. Serial No. 819,452.

To all whom it may concern:

Be it known that I, WILLIAM F. KIESEL, Jr., a citizen of the United States, residing at Altoona, Blair county, State of Pennsylvania, have invented certain new and useful Improvements in Railway-Cars, of which the following is a specification.

My invention relates to improvements in cars and more particularly to improvements in the construction of parts of railway freight cars.

The invention has for its principal object to improve the arrangement of the side and end sheathing and the manner of securing the same in place on a freight car of the box car type.

The above and other objects and the novel features of the invention will be apparent from the following description taken in connection with the drawing, in which—

Figure 1 is a side elevation of so much of a car structure as is necessary to show my invention as applied thereto;

Fig. 2 is an enlarged vertical section of the door on the line 2—2 of Fig. 1, showing parts broken out;

Fig. 3 is an enlarged horizontal section on the line 3—3 of Fig. 1, showing details of the door construction;

Fig. 4 is a horizontal section of a part of the end and side of a car structure embodying my invention;

Figs. 5 and 6 are enlarged sectional views illustrating in detail the construction of the plates and the manner of fastening the same together, the said plates comprising the end and side sheathing, respectively, of the car;

Fig. 7 is a vertical sectional view taken along the line 7—7 of Fig. 1, part being broken away at the center;

Fig. 8 is a cross section on the line 8—8 of Fig. 4, showing a detail of construction;

Fig. 9 is an enlarged detail cross-section of the end of the car showing the attachment of the roof and top of the sheathing;

Figs. 10 and 11 are respectively a plan view and a partial side elevation of a joint connecting two sheathing plates.

Referring to the drawings, the under-frame of the car is arranged somewhat on the order of the passenger car under-frame

shown and described in my Patent No. 809,921. The center sill is made up of two I beams or channel beams 10, one only of which is shown in Fig. 7, which I beams are spaced apart and extend continuously from one end of the car to the other and are fastened together at the top and bottom by cover plates 11, thereby forming a box girder extending through the center of the car. Cross bearers 12 are riveted at intervals to the webs of the channel plates 10 and extend transversely of the car supporting a pair of angle plates 13 and 14 at their outer ends, said angle plates being arranged back to back and riveted to the cross bearers 12. The bracing members 15 are also provided near the ends of the under-frame and support and brace the end 16 of the car.

The horizontal flanges of the angle plates 13 and 14 are on a level with each other and together form the side sill which extends the length of the car at each side and supports the sheathing and inner wooden lining wall 17 of the car. The flange 18 of the angle bar 13 extends inwardly toward the center sill and supports the outer edge of the flooring 19 of the car. The outer bar 14 is made in the form of a channel, one flange 20 of which fits against the vertical flange 21 of the inner angle bar 13 and the other flange 22 forming the outer edge of the car body and being shorter and thicker than the inner flange 20. The web 23 of the sill member 14 forms a horizontal supporting base to which the side sheathing of the car may be riveted.

The side sheathing of the car comprises a series of pressed steel plates, shown in detail in Figs. 4 and 6. Each plate comprises a flat portion 24 and a hollow vertical post or rib 25 pressed into the plate at one vertical edge. Right angle flanges 26 and 27 are formed along the top and bottom edges of the flat portions 24 of the plates and extend from one end of the plate to within a short distance of the hollow rib 25. As is clearly illustrated in Fig. 6 the ends of the flat portions 24 of the plates overlap the hollow portions of the ribs 25 and are secured to opposite sides thereof by the rivets 28 and 29, the other flange 30 being formed beyond the post to receive the rivets. It will be

seen that the flanges of one plate extend across, underneath and above the post 25 on the adjacent plate and abut against the ends of the flanges on the plate carrying the 5 said post, as indicated at 27'. In order to properly brace the post, angle plates 31 are riveted near the lower ends thereof and to the flange 18 of the inside sill member 13. The ribs or posts of the sides and ends of 10 the car extend inwardly and the wooden lining 19 is secured to the inner sides of the posts and terminates short of the bottom 19, leaving a space 201 around the side of the car, openings in the lining being provided 15 for ventilation purposes.

The flanges 26 at the top edges of the plates 24 are riveted to the under side of the horizontal flanges 32 of the angles 33 which have vertically extending flanges 34 for 20 supporting the roof.

As shown in Fig. 7, the roof embodies certain features of the roof shown and described in my Patent No. 961,301 but is adapted to the type of side plates used in 25 this new construction. Carlines 35 are distributed at intervals along the length of the car, as shown in Patent 961,301 and have roof plates 36 secured thereto. The carlines 35 and roof plates 36 have bent downward portions 37 and 38 at their outer ends which are spaced from the vertical flange 34 of the roof supporting angle by a spacer 39 and are riveted to the vertical flange 34. The spacing strips 39 are not continuous, 30 35 ventilating spaces being left on each side of the securing means, as is set forth in Patent No. 961,301.

The end construction of the car differs slightly from the side construction. Two 40 pressed steel plates 40 are riveted to the side plates near the corners 41 and extend inwardly having hollow ribs or posts 42 integral with their inner ends and offset slightly as indicated at 43.

45 A plate 44 overlaps both of the posts 42 at the inner ends of the plates 40 and is placed between the offsets 43 so the end of the car will be even or flush, the plates 40, 40 and 44 together constituting the end of a 50 car with the posts 42, 42 on the interior of the end. As shown in Fig. 4, the side plate adjacent the corner and the end plate adjacent the corner may be pressed from a single sheet, with the hollow posts on the interior 55 at their ends. By curving the same to fit the corner of the car, the riveting may be eliminated. As shown in Figs. 9, 10 and 11, the plates provided with the offset posts may be provided with upper and lower flanges 45 60 to fasten the same to the end sills and roof supporting end angle iron 46. As shown in Fig. 9, the roof plate 47 has a vertically bent portion at its end whereby it is riveted to the vertical supporting flange of the end 65 angle 46.

The side door opening 48 is closed by a sliding door comprising the plates 49 and 50 provided with offset hollow ribs 51 and a lower plate 52, the upper end of which overlaps the hollow part of the lower rib 51 70 and which carries at its lower end an angle member 53 having a part 54 which fits inwardly around the flange 22 on the outer sill member 14. A latch device 50' is provided to lock the door in closed position. At 75 the lateral edges of the plates 49, 50 and 52 are riveted vertical reinforcing bars 55 and 56. At the upper and lower ends of the bars 55 and 56 are riveted hook shaped plates 57, the hooked ends of which fit over 80 the outer depending edges 22 of the side sills to hold the door in place and guide the same as it is moved from open to closed position and vice versa. The vertical plates 55 have an inwardly extending part 58, which, with 85 the angle plate 59 riveted at the opposite side of the door opening, serves to limit the movement of the door to closed position and overlap the meeting edges of the door and door opening. 90

Two upright channel plates 60 at opposite sides of the door are each riveted to an inwardly extending flange 61 of one of the sheathing plates 24 and are braced by suitable angle plates 62 and 63 riveted on the 95 outer side of the web of the channel 60 and the flange 61. The channel members 60 have flanges 64 on the inner side and on the outer side shorter flanges 65 against which abut the inner sides of the plates constituting 100 the door, the flanges 65 projecting the same distance out from the side wall of the car as the flanges 22.

While I have shown and described the structure of the car in detail I wish it to be 105 understood that various changes are possible and the invention is not intended to be limited except as required by the appended claims.

I claim—

1. A railway car body having an end consisting of a pair of plates bent intermediate their ends to provide portions at right angles to one another to form the corners of the car at one end, said plates having integral 115 vertical hollow ribs therein at opposite sides of the center of the end to form hollow reinforcing posts, the ribs in said plates forming corresponding grooves therein opening outwardly, and a plate united to the outer 120 sides of said pair of plates and covering the grooves formed by said ribs.

2. In a railway car body, the combination of a side sill, a roof supporting member, and sheathing consisting of a plurality of plates, 125 each plate having an integral rib near one vertical edge thereof, said ribs being disposed on the inside of the sheathing and their outer open sides being overlapped by plane portions of adjacent plates, the plane 130

portions of said plates having inwardly extending flanges at their upper and lower edges, the flanges of each plate terminating short of the rib thereon, and extending over 5 the ends of the hollow rib on the adjacent plate, and means for securing said flanges to the roof supporting member and side sill.

In testimony whereof I affix my signature in presence of two witnesses.

WILLIAM F. KIESEL, Jr.
